LAMP HOLDER

Jacob Glassberg, Hillside, N. J., assignor to Samson Investment Co., a corporation of New Jersey

Application May 17, 1938, Serial No. 208,382

1 Claim. (Cl. 173—328)

This invention relates to holders or sockets for incandescent lamps, and more particularly to a socket or holder located in a predetermined position with respect to a lens, reflector, refractor or other optical device. In one of its more specific aspects the invention is directed to a holder or socket which permits the installation or removal of a lamp through the top of the holder or socket and which may be readily and accurately located even by an unskilled workman in said predetermined position.

Figure 1 is a vertical cross-sectional view of the lamp chamber of a projection machine embodying the invention.

Figure 2 is a cross-sectional view taken on line 2—2 of Figure 1 in the direction of the arrows.

Figure 3 is a fragment of an enlarged cross-sectional view illustrating the relationship and manner of connecting a contact to the socket chamber.

Figure 4 is a top plan view of my improved holder.

Figure 5 is a cross-sectional view taken on line 5—5 of Figure 4.

Figure 6 is a plan view of the holder shown in Figure 5, but inverted.

Figure 7 is a vertical cross-sectional view of the holder and lamp base.

Figure 8 is a view in perspective of the lamp, base, holder and contact terminal, one above the other.

As shown in the drawings, there is a lamp chamber or housing 10 open at the top and bottom so that a lamp 1 may be inserted therethrough. The lamp 1 is a prefocused lamp and may comprise an envelope 2, a filament 3, and a base 4. Secured to the base are a pair of outwardly extending arcuate wings or lugs 5 and 6. The radius of the outer periphery of the wings are equal, but the length of the arc of the outer periphery of the wings are dissimilar. The wings 5 and 6 are located at a predetermined distance and in a predetermined plane with respect to the filament 3, and bear the same angular relation to the filament, so one lamp may be replaced by another and the position of the filament of the new lamp will be exactly the same as that of the replaced lamp. Secured to the housing 10 and depending therefrom is a chamber or housing 12 for receiving the base of lamp 10. The housing 12 may be composed of an insulating material and preferably an insulating material which may be molded or machined, and is essentially in the form of a hollow cylinder coaxially disposed with respect to the chamber 10. The interior diameter

of the housing 12 is greater than the outside diameter of the envelope of the lamp 1. The interior of the housing 12 has a cylindrical recess extending from its bottom edge up to a point located an appreciable distance from said edge and defines a downwardly facing annular flat shoulder 13 perpendicular to the axis of the chamber 12.

A contact and locating annulus or ring 14 of conducting material has a locating notch or slot 15 in the outer periphery thereof. The outside diameter of the ring 14 is slightly less than the outside diameter of the shoulder 13. The ring 14 is located in said chamber 12 and its upper face is held in abutting relation with shoulder 13 by stud bolts 16 whose conical heads are located in countersinks and above the lower flat face of ring 14. The chamber 12 has an elongated locating and positioning slot or recess 17 therein extending upwardly from the shoulder 13 and this slot or recess 17 bears a predetermined relationship with respect to a lens or other optical device which may be supported by chamber 10. The ring 14 is so disposed on the shoulder 13 that the notch or slot 15 is in alignment with the elongated slot 17 in chamber 12 and the cross-sectional dimensions of the latter are slightly greater than the corresponding dimensions of the former. The inside diameter of the ring 14 is approximately the same as the inside diameter of shoulder 13. A stud bolt 18 carrying a conductor 19 from a source of electric energy extends through the housing 12 and into the contact 14 to make electrical connection therewith.

As shown in Figures 4, 5, 6 and 8 there is a holder comprising a flat annulus or ring conductor 20 having an upwardly extending key or lug 21 integral therewith at its outer periphery. The cross-sectional dimensions of the key 21 are slightly less than the corresponding dimensions of the locating notch or slot 15, and the length of said key 21 is less than the length of recess 17 so that the key may pass upwardly through notch 15 and into the recess 17.

The outside diameter of ring 20 may be slightly less than the outside diameter of shoulder 13 and its inside diameter is just slightly greater than the cylindrical base 4 of the lamp 1 so that the same may pass therethrough. A rigid and thin short cylinder 22 having an outwardly extending flange 23 and an inwardly extending flange 24 is coaxially disposed relative to the ring 20 and is rigidly secured thereto by rivets passing through the ring 20 and flange 23. The outside

diameter of the cylinder 22 is slightly less than the inside diameter of the ring 14 so that the same may be located in the opening of ring 14. The inside diameter of the flange 24 is the same as the inside diameter of the ring 20, and the inside diameter of the cylinder 22 is slightly greater than the corresponding dimension between the wings 5 and 6 of the base of the lamp. A pair of unequal openings 25 and 26 are cut out of the flange 24 and are of approximately the same size as the wings on the lamp 1, with the opening 25 being narrower than wing 6, and are spaced from each other as are said wings so that the lamp may be inserted therein in one way only. And the openings are always located in the same and in a predetermined relationship with respect to the key 21. Struck out of said annular ring 28 are a pair of retaining or locking strips 27 whose free ends 28 are bent upwardly and extend into slots or openings 29 in the flange 24. That portion of each strip under one extremity of the wing shaped openings in flange 24 is inclined gradually upward to the lower face of flange 24 then extends along said lower face and is contiguous therewith from the cam or incline portion thereof to the short upwardly projecting portion of stop 28 which extends through the slot 29.

The shape of the upper face of each spring retaining or locking strip 27 are complements of the lower faces of the wings and the inner extremities of the strips 27 may be spaced a slight distance from the inner face of cylinder 22 so that the downwardly curved outer portion of the wings may make a snug fit therebetween. The position of the stops with respect to the key 21 is always the same and predetermined in order that the position of the filament of the lamp may always be the same with respect to the key 21 and consequently with respect to the optical device.

The holder unit may be readily secured in the chamber 12 by inserting the key 21 through the opening 15 in the contact ring 14 and up into the elongated recess 17 in the side of the chamber. The holder unit is forced upwardly until the upper face of the annular member 23 abuts against the under face of the contact annulus 14. And, in this position, the cylinder 22 is located in the central opening of the annular member 14.

A sleeve 30 is located in the chamber 12 and may be demountable or may be keyed to the

chamber and maintains the holder unit in a fixed position against annular member 14. A closure plug 31 having a contact member 32 secured thereto makes electrical connection between the end terminal of the lamp and the ring 33, connected to a conducting wire 34 by bolt 35. Besides having the advantage of ready assembly with a supporting structure, it is apparent that even an unskilled workman must properly position the same and lamp may be replaced without disturbing an element other than the removal of the burned-out lamp.

When it is desired to mount the lamp in the chamber, the lamp with base down is inserted through the top of the chamber and the base extends through the opening of the holder, the lamp is rotated until the wings 5 and 6 are located in the openings 25 and 26. The lamp is further rotated and upon rotation the wings ride up along the cam portions of the lock springs 27 and as they reach the under face of flange 24 cause the spring to be forced away from the flange 24 and this rotation is continued until the leading edges of the wings 5 and 6 strike the stops 28 to locate the lamp in a predetermined position. The springs 27 maintain the lamp in this fixed position. When it is desired to remove the lamp, the operator inserts his hand through the top of the chamber and counter rotates the lamp to remove the wings from between the spring retainers and the flange 24 and locate the wings in the openings in the flange 24 whereby the lamp may be withdrawn therefrom and a new lamp may be substituted therefor.

Although, the invention has been described in detail, it is not to be limited thereby because it is subject to changes and modifications within its scope.

I claim:

An incandescent lamp holder comprising an annular conducting member, a lug secured thereto adjacent the outer periphery thereof and extending upwardly therefrom, a collar secured to said annular member, a flange extending inwardly from said collar and spaced from said annular member, said flange having a pair of unequally spaced openings therein, a pair of resilient retaining strips struck out of said annular member and normally exerting force in a direction therefrom and towards said flange, and a pair of stops located between said member and said flange.

JACOB GLASSBERG.
